K. VON ELTZ

REGULATING MEASURING VALVE

Filed April 27, 1925

Kuno von Eltz
BY
W. J. Birney
ATTORNEY

UNITED STATES PATENT OFFICE.

KUNO VON ELTZ, OF NEW YORK, N. Y.

REGULATING MEASURING VALVE.

Application filed April 27, 1925. Serial No. 26,817.

My invention relates to regulating measuring valves of the screw-down type in which turning of the screw opens or closes the valve and sets it at the desired position so that a definite amount of steam or liquid will pass. If the position of the valve has to be changed frequently it is often difficult to find the same position when readjusting the valve.

10 One of the objects of my invention is to provide such a valve with an indicating cap attached to the valve, which will permit a very close adjustment of the valve, the cap being of such construction that it may be applied to any standard valve with practically no change in the valve structure.

15 With the above and other objects in view, my invention relates to the parts, improvements and combinations more fully pointed out hereinafter:

20 Referring now to the drawings:

Figure 1 is a front elevation partly in section, showing the valve with the measuring cap attached.

25 Figure 2 is a front elevation showing the measuring cap and the means for securing the pointer to the valve frame, or bonnet.

Figure 3 is a vertical sectional detail view thru the cap and valve stem, on line 30 3—3 of Figure 2.

Figure 4 is a perspective view of the cap when attached, and

Figure 5 is a cross-sectional view on line 35 5—5 of Figure 2, showing two positions for the pointer clamp, one in full lines and the other in dotted lines.

The valve 1, fits upon the valve seat 2, in the valve casing 3, ported at 4 and 5, for the passage of liquid or steam. It may have 40 guiding projections 6 and is carried by the valve stem 7 which passes upwardly thru the frame or bonnet 8, the valve stem being provided with a screw 9. Upon turning the screw by a hand wheel or wrench, the valve 45 is raised and lowered, the screw engaging interior screw threads in the upper part of the frame or bonnet 8.

In accordance with my invention, a measuring cap 10, is provided, which is preferably of cylindrical form, and which may be 50 rotatably adjustable. The measuring cap 10, is provided with means for attaching it to the screw stem. The cap has a head 11, and a skirt 12, the head being provided with

a central perforation 13, and a pair of depending lugs 14, 15. The perforation and lugs can be slipped over the upper part 16, of the valve stem and the cap can thus be removably secured to the stem. It can be locked to the valve stem by means of nut 17 and locknut 18. In this way the measuring cap can be readily applied to the usual form of screw-down valve and rapidly removed therefrom. If a hand wheel is used, it is mounted upon the valve stem in place of the nuts.

The skirt of the measuring cap is provided with a plurality of indicating zones 19, seven of which are shown upon the drawings. Each indicating zone is divided into a suitable number of parts so that a fraction of a revolution of the valve stem may be indicated. In the form shown, one zone corresponds to one revolution of the valve stem and is divided into ten main parts, each main part being divided into four smaller divisions, which number may of course be varied. The distance between two adjacent zones on the skirt of the valve is equal to the pitch of the screw thread 9, on the valve stem so that each revolution of the valve will move a different zone on the skirt into registering relation with the pointer 20.

Means are provided for securing the pointer in a fixed position and in registering relation to the valve cap. The pointer may be screwed or riveted upon the valve casing or frame. In the form of the invention illustrated, I make use of a clamping bracket for securing the pointer in place. The form of clamp may be varied. As illustrated, the clamp comprises two arms 21, 22, to one of which the pointer is secured. Clamping bolts 23, apply the clamping pressure. The clamping arms are notched so as to fit over the frame 8. The pointer will then be in the full view of the operator and the tip of the pointer will register with the zero on the skirt of the measuring cap.

If it is desired to change the position of the pointer so as to keep it in full view of the operator, the clamp may be loosened and the pointer turned 90 or 180 degrees and then the clamp re-tightened. The measuring cap may be correspondingly adjusted.

Having thus described the invention, its operation will be clear. It will be apparent that changes may be made in carrying the

invention into effect, without departing from the principle of the invention.

What I claim is:

1. A measuring screw-down valve in combination with the valve seat, stem and operating screw, of an indicating cap provided with a skirt portion, said skirt portion carrying a plurality of indicating zones arranged along said skirt portion, each zone indicating one revolution of the skirt portion, means for securing said cap to said screw stem so as to turn with it, said cap being provided with a perforated head to fit said stem, a pointer cooperating with said cap and means for securing said pointer to the valve frame.
2. A rotatably adjustable measuring screw-down valve in combination with the valve seat, stem and operating screw, of a removable and adjustable indicating cap provided with a skirt portion, said skirt portion carrying a plurality of indicating zones arranged along the skirt portion, each zone indicating one revolution of the skirt portion, means for securing said cap to said screw so as to turn with it, a pointer cooperating with said cap and a rotatably adjustable clamp carrying said pointer, for securing said pointer to the valve frame in registering relation to the indicator cap.
3. A measuring screw-down valve in combination with the valve seat, stem and operating screw, of an indicating cap provided with a skirt portion, said skirt portion carrying a plurality of indicating zones

arranged along said skirt portion, the distance between the adjacent zones being equal to the pitch of the screw, means for securing said cap to said screw stem so as to turn with it, and a pointer cooperating with said indicating cap.

4. A measuring screw-down valve in combination with the valve seat, stem and operating screw, of a removable indicating cap having a central perforation and one or more depending lugs adapted to embrace the valve stem, said cap provided with a skirt portion, said skirt portion carrying a plurality of indicating zones arranged along said skirt portion, each zone indicating one revolution of the skirt portion means for securing said cap to said screw stem so as to turn with it, a pointer for cooperating with said cap and means for securing said pointer to the valve frame.

5. An indicator for screw-down valves comprising a valve position indicating cap provided with a head and skirt, the head being perforated so as to engage and turn with the valve screw and the skirt carrying a series of revolution indicators, arranged side-by side, lengthwise of the skirt, each one of said indicators giving the portion of a revolution the valve stem has been turned, the series of indicators giving the number of complete revolutions of the valve stem.

In testimony whereof, I have signed my name to this specification.

KUNO von ELTZ.
